(74) Attorney, Agent, or Firm—Thomas M. Freiburger

(22) Filed: **Aug. 24, 2006**

(57) **CLAIM**

The ornamental design for a trash receptacle with liner, as shown and described.

DESCRIPTION

FIG. 1 is a frontal perspective view showing a trash receptacle with liner basket according to my new design;

FIG. 2 is a right side elevation view thereof, the left side elevation being identical and opposite;

FIG. 3 is a top plan view thereof;

FIG. 4 is a bottom plan view thereof;

FIG. 5 is a front elevation view thereof; and,

FIG. 6 is a rear elevation view thereof.
